CLAIM

The ornamental design for a beverage glass or similar article, as shown and described.

DESCRIPTION

FIG. 1 is an elevational view of a beverage glass or similar article showing my new and ornamental design in the size and proportions of a tumbler.

FIG. 2 is a central vertical sectional view thereof.

FIG. 3 is a top plan view thereof.

FIG. 4 is a sectional view taken along and in the direction of sectional plane 4—4 in FIG. 1.

FIG. 5 is a bottom view thereof.

FIG. 6 is an elevational view of my new and ornamental design in the size and proportions of a water glass.

FIG. 7 is an elevational view of my new and ornamental design in the size and proportions of a juice glass.

FIG. 1

FIG. 2
